G. R. PYPER.
ANIMATED SIGN.
APPLICATION FILED SEPT. 27, 1920.

1,382,233.

Patented June 21, 1921.

Inventor:
George R. Pyper

By John Howard McElroy
his Atty.

UNITED STATES PATENT OFFICE.

GEORGE R. PYPER, OF SALT LAKE CITY, UTAH, ASSIGNOR TO PYPER ANIMATED SIGN COMPANY, OF SALT LAKE CITY, UTAH, A CORPORATION OF UTAH.

ANIMATED SIGN.

1,382,233.

Specification of Letters Patent. Patented June 21, 1921.

Original application filed March 12, 1920, Serial No. 365,358. Divided and this application filed September 27, 1920. Serial No. 413,177.

To all whom it may concern:

Be it known that I, GEORGE R. PYPER, a citizen of the United States, and a resident of Salt Lake City, in the county of Salt Lake and State of Utah, have invented certain new and useful Improvements in Animated Signs, of which the following is a full, clear, and exact specification.

My invention is concerned with animated signs employing a novel method by which I impart the appearance of animation to portions thereof. To carry out my invention, I employ a stationary projection surface upon which the animated portion moves, which projection surface is preferably formed of a sheet of opaque or translucent substance upon which a sign or an object may be painted and the portion upon which the movement occurs is preferably provided with numerous comparatively small perforations or substantially transparent portions through which the light from the interior illumination passes, together with a plate or member upon which the animated portion is stenciled and which must be suitably moved and a suitable source of illumination back of the stencil plate to throw the light through the moving stencil on the projection surface.

It is further concerned with a sign containing these necessary elements and means for moving the stencil plate, as well as that certain novel combination of mechanisms by which the necessary elements may be properly grouped and operated.

My present application is in effect a division of my application No. 365,358, filed March 12, 1920, the illustration being the same as sheet 1 of the aforesaid application.

To illustrate my present invention, I annex hereto a sheet of drawings in which the same reference characters are used to designate identical parts in all the figures of which—

Figure 1 is a front elevation of a sign embodying my invention with the major portion of the front wall of the sign receptacle or casing broken away more clearly to disclose the operating mechanism;

Fig. 2 is a horizontal sectional view of the sign receptacle or casing with the operating mechanism shown in plan;

Fig. 3 is a detail sectional view on the line 3-3 of Fig. 1; and

Fig. 4 is a view similar to Fig. 1 showing a different design for the animated portion. Referring to the drawings in detail, the form of the invention shown in Figs. 1, 2 and 3 illustrates the form of sign in which the action of the rising moon is simulated. For this, there is provided a casing 10, in which the front wall 11 forms the projection surface, which front wall is conveniently constructed of metal with a number of relatively small, finely and closely spaced openings or perforations 12 therein which are arranged in the arc of a circle. If the rising of the moon is a part of the landscape effect, all the details desired may be depicted on the front of the plate 11 by painting or otherwise, care being taken not to close the perforations 11 but to leave them translucent. As the moon is seen rising in the sky, the space between the perforations will of course be painted or depicted as representing the sky.

Located within the casing is a lever 13 which is fulcrumed at 14 upon the standard 15. One end of this lever 13 carries a lamp holder in the form of a small casing 16 which is provided with an opening 17 in the front face thereof. As this is intended to represent the rising of a full moon, this opening is a circle. Arranged within the casing 16, directly to the back of the opening, is a source of light 18, preferably a high power incandescent light, the rays of which project through the opening 17. The apparent diameter of this moon will be dependent upon the distance of the filament of light 18 from the aperture 17 and of the aperture from the rear of the casing 11. The arm 13 is so mounted that the source of light will travel behind the projection surface 11 in the arc occupied by the perforations 12, which are preferably covered by a sheet 85 of some translucent material, such as thin cloth or paper, secured on the back thereof, so that a circle of light will move forward with the movement of the lever 13 and be visible through successive circles of openings 12 to simulate a rising moon.

To move the lever 13, its other end is connected by a pitman rod 19 to the eccentrically mounted pin 21 carried by the disk 20 secured on the shaft 22 centrally journaled in the standard 15. Also secured upon the shaft 22 is the large grooved pulley wheel or

disk 23 which is connected by the belt 24 with the small grooved pulley 25 secured on the shaft 26 journaled in the upper end of the standard 27 secured in the casing. The shaft 26 has secured thereon the large grooved wheel or pulley 28 which is connected by the belt 29 with the small grooved pulley 30 on the armature shaft of an electric motor 31 supported in the bottom of the casing. The rapid rotation of the armature shaft of the motor is thus geared down to a comparatively slow rotation of the shaft 22 so that the lever 30 is given a comparatively slow swinging movement.

15 The lamp 18 is connected in a circuit 32, which is indicated diagrammatically as energized by the battery 33, although it will of course be obvious that the current might be derived from any other suitable source, 20 and that some other form of motor and reducing gearing may be substituted for the electric motor and the reducing gearing shown. Also inclosed in the circuit 32 is a circuit breaker carried by the shaft 22 and 25 which comprises rotary contact elements 34 and 35 which are connected by a conductor bar 36. These elements 34 and 35 are engaged by the brushes 37 and these elements are so arranged that as the lever 13 is traveling upward, the lamp 18 will be lighted, 30 and when it reaches its limit of upward movement, the circuit will be automatically broken and will not be again completed until the reverse or last position of the lever is 35 reached.

In Fig. 4, I have illustrated a form of the invention in which the necessary part of the front wall or projection plate 38 of the casing is provided with perforations 39 covering 40 the rear by the translucent sheet 85, as before. Fulcrumed at 42 on a standard within the casing at the rear of the front wall or projection plate is a member 40, which is preferably formed of sheet metal 45 and which is cut to form a stencil of some figure or object, the one shown in the drawings representing a rocking chair 41. This member has connected to one end thereof the pitman rod 43 which is pivoted at its 50 other end on an eccentric pin 44 carried by the disk 45 secured on the shaft 46 journaled in a suitable bearing at the top of a standard on the floor of the casing. The shaft 46 has secured on its other end a large 55 pulley wheel 47 which is connected by the belt 48 with the small pulley 49 secured on the same shaft as the large pulley 50, which shaft is likewise journaled in the standard supported on the bottom of the casing. 60 Belt 51 connects the large pulley 50 with the armature shaft of a motor 52 suitably mounted in the casing. The reducing gearing shown will cause a slow swinging movement of the member 40, and thus produce 65 the appearance of a chair rocking over that

portion of the projection plate 38 having the perforations 39 therein. If the casing is deep, the light 53 may be stationary and located at the rear of the casing at about the middle of the member 40, as shown in Fig. 70 4. Or the light 53 might be supported from the member 40, so as to swing therewith, the stencil 41 in that case corresponding in its action directly to that of the aperture 17 in the other form of the invention illustrated. 75

While I have shown and described my invention as embodied in the form which I at present consider best adapted to carry out its purposes, it will be understood that it is capable of modifications, and that I do not 80 desire to be limited in the interpretation of the following claims except as may be necessitated by the state of the prior art.

What I claim as new, and desire to secure by Letters Patent of the United States is— 85

1. In an animated sign, the combination with a stationary screen plate having a portion thereof containing small, closely spaced perforations therein, of a stencil member mounted to move back of the perforations 90 and having the animated object stenciled therein, means for moving the stencil member, and a light back of the stencil member so that the rays therefrom pass through the stencil and form a moving object outlined 95 on the field of perforations through successive groups of which the outlined object is visible as it appears to move.

2. In an animated sign, the combination with a stationary screen plate having a portion thereof containing small closely spaced perforations therein, of a stencil member mounted to move back of the perforations and having the animated object stenciled therein, means for moving the stencil member, and a light carried back of and with the stencil member so that the rays therefrom pass through the stencil and form a moving object outlined on the field of perforations through successive groups of 110 which the outlined object is visible as it appears to move.

3. In an animated sign, the combination with a stationary screen plate having a portion thereof containing small closely spaced 115 perforations therein, of a stencil member fulcrumed to move back of the perforations and having the animated object stenciled therein, a pitman rod connected to the stencil member, a shaft having an eccentric pin 120 to which the other end of the pitman is connected, an electric motor, and reduction gearing from said motor to said shaft.

In witness whereof, I have hereunto set my hand and affixed my seal, this 11th day 125 of June, A. D. 1920.

GEORGE R. PYPER. [L.S.]

Witness:

JOHN HOWARD McELROY.
